(57) **CLAIM**

The ornamental design for an endoscope, as shown and described.

DESCRIPTION

FIG. 1 is a front perspective view of an endoscope according to the present invention.

FIG. 2 is a right side elevational view of the endoscope of FIG. 1.

FIG. 3 is a left side view of the endoscope of FIG. 1.

FIG. 4 is a top view of the endoscope of FIG. 1.

FIG. 5 is a bottom view of the endoscope of FIG. 1.

FIG. 6 is a front perspective view of the endoscope of FIG. 1; and,

FIG. 7 is a rear view of the endoscope of FIG. 1.

The broken away symbols in the drawings indicate that any portion of the article beyond what is shown forms no part of the claimed design.
